UNITED STATES PATENT OFFICE.

REBECCA C. HOWARD, OF OTAY, CALIFORNIA.

BOOK-COVER PROTECTOR.

1,209,967.

Specification of Letters Patent.

Patented Dec. 26, 1916.

Application filed October 7, 1914. Serial No. 865,534.

To all whom it may concern:

Be it known that I, REBECCA C. HOWARD, a citizen of the United States, residing at Otay, in the county of San Diego and State 5 of California, have invented certain new and useful Improvements in Book-Cover Protectors, of which the following is a specification.

This invention relates to book-covers and 10 more particularly to a protector for the same.

The object of my invention is to provide a detachable protector for a book-cover which is simple in construction, cheap to manufacture, durable and easily attached to the 15 cover of a book.

Another object of my invention is to provide a cover which when placed upon a book and folded into engagement with the cover 20 thereof can not become disengaged or loose upon the cover of the book.

The principal feature of my invention resides in the manner in which the flaps of 25 the protector are cut and folded together so as to prevent accidental disengagement.

With the above and other objects in view my invention resides in the construction, combination and arrangement of parts as set forth in the following specification and 30 illustrated in the accompanying drawings, in which:—

Figure 1 is a perspective view of a book having the cover open and provided with my improved protector. Fig. 2 is a transverse 35 sectional view through the cover of a book showing the arrangement of my protector thereon. Fig. 3 is an inside view of the cover protector, one half of the same being folded and the other half being partially opened. 40 Fig. 4 is a plan view of the blank showing the cover protector before folding.

Similar reference characters indicate similar parts throughout the various views of the drawings.

Referring more particularly to the drawings in which the preferred embodiment of my invention is illustrated I provide a book-cover protector having a body portion 1 which is divided into three portions 2, 3 and 45 16 by the creases or lines 4, these portions 2 and 3 being adapted to embrace the back and front 5 and 6 of a book-cover, this being shown to advantage in Fig. 2. The body portion 1 of the book-cover is provided with 50 top flaps 7, said top flaps 7 being adapted to fold upon the line 8, this line marking the

marginal edge of the body portion 1 when all of the flaps are folded. End flaps 10 and 11 are provided, these flaps being adapted to fold on the lines 8. Bottom flap 9 is formed 60 substantially in a manner similar to the flaps 7, the inner or adjacent sides of the said flaps 7 and 9 being inclined as shown at 12 and 13 and converged toward the point at which the flaps 7 are folded upon the 65 body portion 1. Supplemental flaps or tongues 14 are provided by slitting the top and bottom flaps along the lines 7' and 9'. The tongues 14 are adapted to be folded upon the portion 15 of the line 8 at the 70 points 15 and strengthen the portion 16 of the body portion 1 which is embraced between the two creases or lines 4, when the two portions 2 and 3 of the cover protector are engaging the cover of a book. As will 75 be noted to advantage in Fig. 4 these tongues 14 are substantially of a width equal to the width of the portion 16, and the converging edges 12 and 13 of the flaps 7 and 9 terminate at the outer edge of the flap 14 as indicated at 17. The side flaps 10 and 11 are adapted to be folded as stated above on the lines 8, and the said flaps 10 and 11 are folded upon themselves on the lines 18, thereby providing supplemental flaps 19 85 and 20, the said flaps 19 and 20 being folded upon the lines 18 at such an angle as to conform to the slanting or converging lines 12 and 13 of the flaps 7 and 9 when the cover protector is in engagement with the cover 90 of a book.

When it is desired to apply the cover protector to a book-cover the back and front of the book are open and laid flat on the body portion 1 of the protector. The flaps 9 are 95 then folded upon the cover of the book and the tongues 14 are inserted between the back 21 and the binding 22 of the book. The flaps 7 are now folded upon the flaps 9 and in order to lock the same in position the side flaps 10 and 11 are folded upon the flaps 7 and 9, the supplemental flaps 19 and 20 carried by the flaps 10 and 11 being inserted between the flaps 7 and 9 and engaging the flaps 7, this being indicated to advantage at 23 in 100 Fig. 3. Since the flaps 19 and 20 are folded on the lines 18 at such an angle as to engage the marginal edges 12 and 13 of the flap 7 it is impossible for the flaps 7 and 9 to become disengaged from the book-cover, 105 this only being rendered possible by removal of the flaps 19 and 20 from engagement with 110

the flaps 7. The portion 16 of the body 1 is adapted to embrace the name plate 21 of the book so that the book when provided with my improved cover protector is entirely protected from dust and dirt and other like damage. The manner in which the flaps 19 and 20 engage the flaps 7 is shown to advantage in Fig. 2, it being noted that the flap 19 is folded at the point 18 and inserted between the flap 7 and the flap 9 of the book. The flap 20 is folded in a similar manner and need not be dwelt upon further at this time. The leaves of the book are indicated by the numeral 22', and it can be readily noted from the drawing the exact manner in which my device is applied to a book cover.

From the above it is thought that a clear and comprehensive understanding of the construction and application of my invention can be had, and it will be readily noted and appreciated by those skilled in the art that I have provided a book-cover protector which is simple in construction, cheap to manufacture and readily applied to a book cover to protect the same.

While I have shown and described my in-

vention as possessing a peculiar form and construction it is desired that it be understood that I may make such changes in the detail formation and construction of the device as do not depart from the spirit and scope of the invention as claimed.

Having thus described my invention what I claim and desire to secure by Letters Patent, is:—

A book-cover protector, comprising a body portion, pairs of top and bottom flaps, and a pair of opposing side flaps attached to the body portion, all of said flaps lying in overlapped relation to the body portion, the bottom flap of each pair lying between the corresponding flap of the top pair and the body portion, and the corresponding side flap overlying the top flap, the ends of each of said side flaps lying between the top and bottom flaps.

In testimony whereof I affix my signature in presence of two witnesses.

REBECCA C. HOWARD.
